United States Patent Office.

W. B. CARGILL, OF NEW HAVEN, CONNECTICUT, ASSIGNOR TO HIMSELF AND I. STROUSE AND COMPANY, OF THE SAME PLACE.

Letters Patent No. 73,873, dated January 28, 1868.

IMPROVEMENT IN FASTENINGS FOR CORSETS.

The Schedule referred to in these Letters Patent and making part of the same.

TO ALL WHOM IT MAY CONCERN:

Be it known that I, W. B. CARGILL, of New Haven, in the county of New Haven, and State of Connecticut, have invented a new Improvement in Corset-Clasps; and I do hereby declare the following, when taken in connection with the accompanying drawings, and the letters of reference marked thereon, to be a full, clear, and exact description of the same, and which said drawings constitute part of this specification, and represent, in—

Figure 1, a front view.

Figures 2 and 3, the blanks.

Figure 4, a sectional view, and in

Figure 5, a rear view.

This invention relates to an improvement in the construction and manner of securing the clasps to corset-steels.

To enable others to construct my improvement, I will proceed to describe the same, as illustrated in the accompanying drawings.

A is the one steel, and B the other, such as are commonly used. The eye and button are usually secured one to each of the steels, by riveting thereto. This riveting not only weakens the steels, but bends or springs them out of shape. I overcome these objections by forming the button, first cutting a blank, C, from sheet metal, as seen in fig. 2. Then bend the tongue *a* up, as seen in fig. 4. Then, placed upon the steel, the end *d* of the blank and the end *f* are turned down, and clasped tightly around the steel, as seen in figs. 4 and 5, by swaging or equivalent means. The eye D is cut from similar sheet metal, as seen in fig. 3, and placed upon the steel. The tongues *c* and *e* are turned down, and clasped securely around the steel, as seen in figs. 4 and 5, and the eye and button are clasped so firmly as to be immovable on the steels, and therefore tend to strengthen the steels, and no riveting is required, the button being formed from one and the same piece as the plate to which it is attached. The two parts are clasped and unclasped in the usual manner, and by this construction the steels are produced at no more cost than those riveted in the usual manner, and are superior, inasmuch as they overcome all objections to the common steels.

I do not wish to be understood as broadly claiming placing the hook or eye around their respective steels.

Having thus fully described my invention, what I claim as new and useful, and desire to secure by Letters Patent, is—

The within-described corset-fastening, consisting of the hook and eye, formed as shown, and secured to the steels without riveting, as herein set forth,

W. B. CARGILL.
